UNITED STATES PATENT OFFICE.

FRANK J. GILROY, OF BUFFALO, NEW YORK.

TIE-TAMPER.

No. 917,860.

Specification of Letters Patent.

Patented April 13, 1909.

Application filed December 26, 1907, Serial No. 408,220. Renewed September 11, 1908. Serial No. 452,660.

To all whom it may concern:

Be it known that I, FRANK J. GILROY, citizen of the United States, residing at Buffalo, in the county of Erie and State of New York, have invented certain new and useful Improvements in Tie-Tampers, of which the following is a specification, reference being had therein to the accompanying drawing.

This invention relates to power operated tie tampers especially adapted for use without interfering with the running of trains or with ordinary block signal systems, no connection being made between the right hand and left hand rails, and no parts being so mounted that they cannot be instantly removed from the path of a train by one man, or indeed be thrown aside by the train itself should a train by any chance strike the apparatus.

Practically, it is desirable that tamping be done only under and for short distance on each side of each rail, lest the tie rock upon the ballast under its middle. With these points in view, I provide one or more tampers to act under and alongside one rail, preferably without connections extending to the companion rail. Each tamper is handled by one man, being detachably engaged with, and supported by, the rail or ties and moved from side to side of the rail and from tie to tie, as desired, by the operator, the whole apparatus being so light as to be readily handled, as a power operated tool, by one person.

In the accompanying drawings, Figure 1 is a perspective view of the apparatus in working position. Fig. 2 is an enlarged view of part of the cylinder and handle broken away to show a fluid conduit. Fig. 3 is a cross section of a rail with a certain support mounted thereon. Fig. 4 is a plan view of the support of Fig. 3. Fig. 5 is a detail section of a cylinder clamping device. Fig. 6 is a side elevation showing a modified construction. Fig. 7 is a perspective view of a modified support seen also in Fig. 6. Fig. 8 is a section at 8—8, Fig. 6.

In Figs. 1, 2, A represents an ordinary rail resting upon any suitable ties B, and C a cylinder having a tool-carrying plunger rod D which is caused to reciprocate rapidly by means of fluid, preferably air, under pressure brought to the apparatus by a flexible pipe E within the cylinder and valve chest F, and the tool-carrying devices are wholly without novelty and except the latter, are not shown.

The cylinder is shown as provided at its upper end with a handle G and to one side of this handle the pipe E is attached. The fluid passes from the pipe E through a passage G' in the handle and thence along a passage G² in the wall of the cylinder to the interior of the valve chamber F. The handle is provided at a convenient point with a valve H normally closed by the fluid pressure but held open, when the tool is operated, by pressure of the thumb or finger upon the valve; whereby air is cut off instantly when tamping is not desired. To support the cylinder I provide a vertical preferably tubular standard I having a base plate I' to rest upon the rail. The base plate has on one side a rigid hook I² to engage the lower side of the rail head and upon the opposite side an analogous hook I³ hinged to the plate and provided with a spring I⁴ for yieldingly holding this hook also in engagement with the rail head. If now the standard be mounted on the rail its rigid hook positively resists force tending to push it in one direction while its spring hook resists a moderate force acting in the contrary direction but is disengaged by a stronger force. Upon the standard are adjustably fixed collars I⁵, I⁶ and between them is held a collar having a horizontal arm J to support the cylinder C. This arm may be locked against rotation on the standard by a set screw J'. The cylinder is provided with an external dovetail groove C' in which lies the head of a bolt K and upon this bolt is a loose sleeve K' which coacts with the bolt head to grip the flanges of the groove when a wing-nut K² is screwed inward on the bolt. Upon the sleeve K' is loosely mounted a block K³ which also slides freely upon the arm J. The standard, being mounted on the rail, its arm is adjusted at any desired height and approximately parallel to the ties and is locked to the standard, the cylinder is set at the desired height and locked at that height by the wing-nut K², and a suitable tamping bit or tool D' is secured in the tool holder. The handle at the upper end of the cylinder is grasped and the spring valve is pressed inward opening the passage and admitting fluid to the valve chest. This causes rapid reciprocation of the tamping tool, which is variously inclined in the same plane by rocking the cylinder with respect to the block K³ and in a different plane by rocking it and said block on the arm J, these movements or any desired combination of

them being given by the hand which grasps the handle. The rigid hook I^2 is always placed upon that side of the rail upon which the tool is to work and hence the standard 5 rigidly resists the reaction of the blows struck by the tool. It is obvious that the tool may be so inclined as to drive ballast beneath the tie at a point directly below the rail as well as at all points not greatly more 10 distant from the rail than the free end of the arm J . When one side has thus been tamped the standard may be slid along the rail to bring the tool in position to operate upon the other side. When it is desired to tamp 15 upon the opposite side of the rail, the standard with all the parts supported thereby, is swung toward the side upon which the cylinder may be, whether between the rails or otherwise, detached from the rail and then 20 replaced with the rigid hook upon the opposite side of the rail so that it may again resist the reaction of the blows. The whole operation requires less time than the description, and obviously the whole apparatus 25 may be almost instantly removed from the roadway if desired, although the spring hook prevents the weight of the cylinder from detaching the standard from the rail should the operator cease to hold the apparatus.

A modified construction, illustrated in Figs. 6, 7, 8 discards the standard and uses a plate or base L to rest upon one or more of the ties, the base having its end L' bent down 35 to engage the lateral face of the tie. To this bent base, near its bent end, is hinged a plate M provided with one or more transverse slots M' . The sleeve N and bolt O are made shorter than the corresponding sleeve and 40 bolt of the first form but both pass through the slot M' and as before the cylinder is locked to the bolt and sleeve, but not locked to the plate by the wing-nut, adjustment being had by sliding the cylinder longitudinally as before, and by moving it bodily 45 along the slot. The plate M is supported at its free end by a rod P provided with a turn-buckle P' for varying its length. In using this form the foot of the operator is placed 50 upon the plate L , and the reaction is against the tie instead of the rail. It is evident that two of these tampers may be used simultaneously upon opposite sides of the same tie and that one or two others may be used at the 55 same time at the opposite ends of the ties, any number up to the limit of the air supply may be operated from the same source of power, which is usually a compressor at some distance from the working point.

60 What I claim is:

1. The combination with a power-actuated tie tamping mechanism, of a supporting base adapted to rest upon the roadway structure at one side of the medial line thereof and 65 provided with means for engaging said struc-

ture and resisting lateral movement while permitting the base to be lifted, and devices connecting said mechanism and devices adapted to permit the former to swing both vertically and from side to side, substantially as set forth. 70

2. The combination with a supporting base adapted for resting upon the roadway structure at one side of the medial line thereof and for laterally engaging the same to resist sliding while permitting the lifting of the base by the hand, of power-actuated tie-tamping mechanism supported from the base by devices permitting the mechanism to slide toward and from said structure and to 75 swing upon both horizontal and non-horizontal axes. 80

3. The combination with a supporting base adapted to rest upon the roadway structure upon one side of the medial line of the roadway, of power actuated tie tamping mechanism supported from said base by devices permitting the adjustment of the distance of the mechanism from the road bed and the swinging of the mechanism in vertical 85 and non-vertical planes, and means for resisting the sliding of the base from the tamping point while permitting the whole apparatus to be lifted and freed from the roadway structure. 90

4. The combination with a standard having a base adapted to rest upon one rail and engage beneath one side thereof, of an arm projecting laterally from said standard, and a power-actuated tie-tamping mechanism 100 mounted to slide freely along said arm and to swing in vertical and non-vertical planes.

5. The combination with a standard having a base which is adapted to rest upon a rail and is provided with a rigid projection to 105 engage beneath one side of the rail and prevent swinging of the standard to the opposite side, of devices for yieldingly resisting swinging of the standard in the opposite direction, an arm projecting laterally from the 110 standard, and power-actuated tamping devices mounted to slide along said arm.

6. The combination with an upright standard adapted to rest upon a rail, of an arm projecting from the standard and rotatable thereon, means for adjustably fixing the height of the arm while leaving it free to rotate about the standard, and a power-actuated tie-tamping mechanism mounted to slide along said arm and to swing freely 115 in vertical and non-vertical planes. 120

7. The combination with a rigid horizontal arm and means for supporting the same from a single rail, of a cylinder mounted to slide freely both along said arm and transversely with respect thereto, and to swing freely in both vertical and non-vertical planes, means for locking the cylinder at any point in its transversely sliding path, a tool-carrying reciprocating member in said cylinder 125 130

der, and means for applying power to reciprocate said member.

8. In tie tamping apparatus, the combination with a standard adapted to rest upon a rail and provided upon one side with a rigid device for engaging a projecting part of the rail and preventing movement of the standard toward the opposite side, of a rigid arm projecting from the standard upon the same side as said device, and a tool-carrying fluid pressure cylinder adjustably secured upon said arm.

9. The combination with the standard

having the laterally projecting arm and provided at its lower end with the rigid hook 15 upon one side and the spring hook upon the opposite side, of a tool-operating fluid pressure cylinder adjustably secured upon said arm.

In testimony whereof I affix my signature 20 in presence of two witnesses.
